INTERLOCKABLE FILE RACK UNIT

Herbert Rome, Los Angeles, and Erland G. Paulson,
Huntington Beach, Calif., assignors to Eldon Industries,
Inc., Hawthorne, Calif.

Filed Dec. 12, 1969, Ser. No. 20,480

Term of patent 14 years

Int. Cl. D6—01

U.S. Cl. D33—3

FIG. 1.

FIG. 7.

FIG. 2.

FIG. 3.

FIG. 4.

FIG. 5.

FIG. 6.

FIG. 1 is an isometric view showing the front and side of an interlockable file rack unit embodying the new design of the invention;

FIG. 2 is a side elevational view of the structure shown in FIG. 1;

FIG. 3 is a front-elevational view of the interlockable file rack unit shown in FIG. 1;

FIG. 4 is a rear-elevational view of an interlockable file rack unit shown in FIG. 1;

FIG. 5 is a top-plan view of the interlockable file rack unit shown in FIG. 1;

FIG. 6 is a bottom-plan view of the interlockable file rack unit shown in FIG. 1;

FIG. 7 is an isometric view of the interlockable file rack unit shown in FIG. 1, showing the rear and one side thereof.

We claim:

The ornamental design for an interlockable file rack unit, substantially as shown.
